Patented Jan. 10, 1928.

UNITED STATES PATENT OFFICE.

EDGAR D. MISNER, OF DETROIT, MICHIGAN, ASSIGNOR TO LOVELL MANUFACTURING COMPANY, OF ERIE, PENNSYLVANIA, A CORPORATION OF PENNSYLVANIA.

WRINGER DRAIN BOARD.

Application filed September 4, 1923. Serial No. 660,892.

The invention relates to drain boards for wringers and more particularly to drain boards for wringers used upon portable washing machines.

One of the objects of the invention is the provision of a drain board of simple construction and light weight which can be easily shifted upon the wringer frame to direct the water as it drops from the clothes passing between the wringer rolls, to either side of the wringer frame.

Another object is the provision of a drain board which is mounted upon and guided by the tie connection between the upright members at the ends of the wringer frame, this tie connection further limiting the movement of the drain board.

A further object is the provision of means upon the wringer frame for collecting and guiding the water as it drops from the clothes passing between the wringer rolls, to a comparatively narrow outlet opening above the drain board, this means being yieldable in the event that the clothes wrap around the lower wringer roll.

With these as well as other objects in view, the invention resides in the novel features of construction and combinations and arrangements of parts as more fully herein-after set forth.

In the drawings:

Figure 1 is a side elevation of a wringer embodying my invention;

Figure 2 is a cross section on the line 2—2

35 of Figure 1;

Figure 3 is a top plan view of the drain board.

The wringer frame comprises the complementary sections 1 and 2 which together form the upright members 3 at the ends of the frame in which are journalled the upper and lower rolls 4 and 5 respectively, the upper roll being vertically movable toward and away from the lower roll. 6 and 7 are spaced parallel tie rods extending between the lower ends of the upright members 3 and forming the tie connection therebetween.

The drain board 8 is mounted upon and guided by the tie rods 6 and 7 and furthermore its endwise movement transversely of the wringer frame is limited by these tie rods. As shown, the drain board proper has the downwardly and outwardly inclined

aprons 9 and 10 and the intermediate ridge 11. 12 and 13 are upwardly extending flanges at the side edges of the aprons 9 and 10 respectively, these side flanges terminating short of the ridge. 14 are plates secured to the side flanges 12 and 13 as by means of rivets, each plate being provided with a longitudinally extending elongated opening 15 located below the upper end portions of the aprons 9 and 10. The side flanges 12 and 13 have their upper end portions offset inwardly a sufficient distance so that the outer sides of the plates 14 are substantially flush with the outer sides of the remaining portions of the side flanges. The tie rods 6 and 7 extend through the elongated openings 15 and the length of these openings as well as the location of their ends is such that upon longitudinal shifting of the drain board in either direction, either the one tie rod or the other will engage the corresponding ends of the elongated openings to limit the movement of the drain board so that its ridge will be to one side of the vertical plane through the axes of the wringer rolls.

In order to provide a drain board which is of simple construction and of light weight, each of the plates 14 and also the drain board proper including the aprons 9 and 10 with their side flanges 12 and 13 and the ridge 11 are formed of stampings, the side flanges 12 and 13 terminating short of the ridge to permit the drain board proper to be formed by a stamping operation.

For the purpose of collecting and guiding the water as it drops from the clothes passing between the wringer rolls, to a comparatively narrow outlet opening so that the drain board may have the minimum longitudinal adjustment in either direction, I have provided the pair of complementary wings 16, each wing having the depending curved portion 17 substantially concentric with the lower roll 5, the outwardly and downwardly inclined apron 18 extending from the upper edge of the curved portion 17 and the pair of arms 19 extending upwardly from the side edges of the aprons and pivotally connected at 20 to the wringer frame. The curved portions 17 extend below the lower roll 5 as well as below the inwardly extending flange 21 upon the wringer frame and terminate short of the vertical plane passing through the axes of the rolls whereby

the curved portions of the two wings form a comparatively narrow outlet opening 22 extending longitudinally below the lower roll through which the water may pass after 5 it has dropped from the clothes. By reason of this comparatively narrow outlet opening it is necessary only to move the drain board longitudinally a sufficient distance to bring its ridge to either side of the opening to control 10 the direction of flow of the water upon the drain board. Both the wings 16 are also formed of stampings and as a consequence are of light weight and may be cheaply manufactured. Furthermore the wings being 15 pivotally mounted upon the wringer frame are free to move outwardly in the event that the clothes wrap around the lower roll, thereby avoiding the possible damaging of the clothes.

20 From the above description, it will be readily seen that I have provided a simple light construction of drainboard formed of a stamping and mounted upon and guided by the tie connection at the bottom of the 25 wringer frame. It will also be seen that the wings for collecting and guiding the water as it drops from the clothes are retained in their normal positions by gravity and are free to move outwardly and away from the 30 lower roll if the clothes wrap around the same. Still further it will be seen that my drain board will be automatically positioned upon passing clothes between the wringer rolls since the depending portions of the 35 clothes will engage the apron over which they are ascending and exert a force to move the drain board longitudinally. These clothes also upon descending upon the apron at the other side of the wringer frame and 40 passing down thereover will exert a force tending to hold the drain board in its adjusted position.

What I claim as my invention is:

1. The combination with a wringer frame 45 and rolls journalled therein, of spaced substantially parallel tie rods extending across said frame below said rolls, and a drain board provided with an elongated opening through which said tie rods pass, said opening being elongated longitudinally of said drain board and said drain board being lon-

gitudinally adjustable transversely of said frame.

2. The combination with a wringer frame and a pair of rolls journalled therein, of a pair of spaced substantially parallel tie rods extending across said frame below said rolls, and a drain board mounted upon said tie rods, said drain board having downwardly and outwardly inclined aprons and an intermediate ridge and being provided with longitudinally extending elongated openings below the upper end portions of said aprons, said tie rods extending through said openings and being engageable with the ends thereof to limit the longitudinal movement of said drain board.

3. The combination with a wringer frame and rolls journalled therein, of a drain board 70 slidably mounted upon said frame below said rolls, said drain board comprising a stamping having downwardly and outwardly inclined aprons and an intermediate ridge and also upwardly extending flanges at the sides of said aprons, said flanges being cut 75 out at the center permitting the upbending of the ridge, said drain board also having a pair of stampings secured to said side flanges closing the cut-out portion of the flanges and provided with means below the upper 80 end portions of said aprons for slidably engaging said frame.

4. The combination with a wringer frame and a pair of rolls journalled therein, of a pair of complementary wings pivotally 85 mounted upon opposite sides of said frame and provided with depending curved portions extending below said rolls and having their adjacent ends spaced from each other.

5. The combination with a wringer frame 90 and a pair of rolls journalled therein, of a pair of complementary wings pivotally mounted upon opposite sides of said frame, said wings having depending curved portions extending below said rolls and having 95 their lower ends spaced from each other, said wings also having outwardly extending aprons engageable with the clothes passing between said rolls.

In testimony whereof I affix my signature.

EDGAR D. MISNER.
